UNITED STATES PATENT OFFICE.

JOHN W. GRAHAM, OF PRAIRIE DEPOT, OHIO.

IMPROVEMENT IN IMPLEMENTS FOR CONSTRUCTING RAIL FENCES.

Specification forming part of Letters Patent No. 151,116, dated May 19, 1874; application filed April 10, 1874.

To all whom it may concern:

Be it known that I, JOHN W. GRAHAM, of Prairie Depot, in the county of Wood and State of Ohio, have invented a new and Improved Fence-Rail Holder; and I do hereby declare that the following is a full, clear, and exact description of the same, reference being had to the accompanying drawing forming a part of this specification, in which—

Figure 1 is a perspective view; and Fig. 2 a vertical cross-section, of post.

The invention relates to means whereby the rails or longitudinal boards, which are usually affixed by nails or other fastenings to the fence-posts, may be spaced at exactly the intervals desired and in a corresponding manner on all the panels. The invention consists in a rail-gage constructed, put together, and operated substantially as hereinafter described, and subsequently indicated in the claim.

A represents the ordinary posts of a plank or board fence, placed at such distance apart as is preferred, and B the rails, which may be all of the same length, or some long and others short. C is my improved rail-gage, con-

sisting of the long-slotted piece c, rigid head-piece c¹, pivoted catch c², sliding blocks c³, and clamp-screws c⁴.

The application is as follows: The posts A having been planted or firmly secured at the bottom, the top rail carefully fastened in position, and the blocks c³ placed precisely at the relative distances apart, which correspond to the intended intervals between the rails, the gage C is hung by the rigid block c¹ on the top rail, and the catch turned down to prevent its escape. The rails are then caused successively to rest upon the blocks c³, while the ends of each are nailed upon the two posts.

Having thus described my invention, what I claim as new is—

A rail-gage, consisting of slotted piece c, head piece c¹, pivoted catch c², adjustable blocks c³, and clamp-screws c⁴, as set forth.

JOHN W. GRAHAM.
